BUFFING MEANS FOR RAILWAY CARS
AND THE LIKE

Frederick W. Hankins and Wendel J. Meyer,
Philadelphia, Pa., assignors to The Pennsylvania Railroad Company, Philadelphia, Pa., a corporation of Pennsylvania

Application December 27, 1941, Serial No. 424,586

15 Claims. (Cl. 213—8)

This invention relates to buffing means for railway cars and the like, particularly to buffing means of the type in which the cushioning units are of composite construction, i. e., formed by a pack of flat resilient pad-like spring elements in alternation with dividing or separating plate elements.

While considered from certain aspects, our invention has reference to railway car buffing means generally, it is more specifically concerned with buffing means useful in connection with railway cars having sliding center sills to the opposite ends of which suitable draft or coupler gears are connected.

Amongst the objects of our invention are to attain the advantages of reduced manufacturing costs which result from simplified construction of railway car buffing means including those of the type specifically mentioned; and to make possible quick and easy assembling and placement of the component parts of such means in proper position in the underframe of the car structures without requiring the exertion of excessive manual effort and without danger of injury to the shop crews assigned to such work.

Other objects and attendant advantages will appear from the following detailed description of the attached drawings, wherein; Fig. 1 is a fragmentary view in top plan of a railway car with buffing means conveniently embodying our invention in one form, portions of the floor of the car having been broken out to expose the underlying parts.

Fig. 2 is a view partly in plan and partly in horizontal section of the central portion of the car body drawn to a larger scale to show the details of the buffing means to better advantage.

Fig. 3 shows a fragmentary view of the car body in longitudinal section, taken as indicated by the angled arrows III—III in Figs. 1 and 2.

Figs. 4, 5, 6 and 7 are fragmentary cross sectional views taken as indicated respectively by the angled arrows IV—IV, V—V, VI—VI and VII—VII in Figs. 1, 2 and 3.

Fig. 8 is a fragmentary view corresponding to Fig. 3 showing the initial step in the placement of the spring unit of the buffing means in the car body.

Fig. 9 is a fragmentary plan sectional view taken as indicated by the angled arrows IX—IX in Fig. 8.

Fig. 10 is a view like Fig. 8 showing an intermediate step in the placement of the spring unit.

Fig. 11 is a plan sectional view corresponding to Fig. 10 with portions of the frame of the car

body broken away to expose the spring unit, and with the retaining member for the unit in position and secured.

Figs. 12 and 13 are perspective views of the implements which we have provided in accordance with our invention to facilitate assembling and placement of the spring unit.

Fig. 14 is a view in longitudinal section corresponding to Fig. 8 showing an alternative embodiment of our invention.

Fig. 15 is a longitudinal sectional view showing an intermediate step in the assembling and placement of the spring unit of the alternative form of buffing means.

Fig. 16 is a plan view corresponding to Fig. 15; and

Fig. 17 is a view corresponding to Fig. 10 showing a modified implement for use in assembling and placing the spring unit of the alternative embodiment.

With reference first to Figs. 1—7 of these drawings, the numeral 1 comprehensively designates the sliding center sill of the railway car, the same being disposed in a longitudinal guideway formed between a pair of laterally spaced opposingly arranged channels 2 which constitute the stationary center sill of said body. The cross bearers 3 of the underframe in this instance comprise aligned lateral web plates 3a, see Fig. 6, whereof the inner ends fit into the hollows of the stationary channel bars 2 whereto they are welded, and tension members in the form of straps 3b which are riveted fast to the lower flanges respectively of said channel bars and said web plates 3a. In the plane of each cross bearer 3, the channels 2 are rigidly connected by a built-up filler piece 4 of T configuration whereof the oppositely projecting portions of the cross arm overreach the laterally spaced side channel members or longitudinals 5 of the sliding sill 1. From Fig. 6 it will be further noted that the outer ends of the cross arm of the filler piece 4 are butt-welded to the inner faces of the stationary channel bars 2, and that the strap 3b of the cross bearer 3 is riveted to the bottom flange of said filler element. The construction of the frame bolsters 6 (Fig. 1) may be generally similar to that of the cross bearers 3, and support at their outer ends, the side sill bars 7 of the side girders. The floor of the car body is formed by sheets 8—8 which are supported by the fixed sill bars 2, the cross bearers 3, the bolsters 6 and the side sills 7 to which they may be riveted or otherwise secured. As shown in Fig. 6, the inner edges of the floor plates 8 are substantially in line with the inner faces of the

center sill channels 2 and are overlapped by the side edge margins of a center strip 10 which closes the space between the fixed center sill channels 2 at the top, said center strip being anchored by the rivets which secure the inner edges of said floor plates. At intervals along the length of the sliding center sill 1, the side channels 5 are rigidly connected by upper and lower bridging plates 11 and 12 which are secured to the top and bottom flanges of said channels preferably by welding as shown in Fig. 7.

For the purpose of yieldingly resisting endwise movement of the sliding center sill 1 relative to the underframe of the car in either direction, there is provided, in accordance with our invention, the buffering means comprehensively designated by the numeral 15. As shown, this buffering means includes a spring unit composed of multiple flat spring elements 16 which are serially arranged in alternation with metallic spaced plates 17. The elements 16 are of a commercially available type, each consisting of plural rings of rubber 18 or the like, one within the other, carried by a center plate 19 with projection beyond both sides of the latter, see Figs. 2-4. The spring unit is under a definite degree of normal compression in the car assembly and the endmost of the resilient elements abut pressure plates 20, which, in turn, normally bear against stops 21 secured to and projecting inwardly from the inner faces of the side channels 5 of the sliding center sill 1. As shown, the stops 21 are of composite construction with their component parts welded fast to each other and to the channels 5. From Figs. 2 and 3 it will be seen that the pressure plates 20 also abut positionally fixed stops 22 which are apertured as at 23 for passage of locking pins 24 through them. At their upper ends the pins 24 engage in pockets 25 provided by hollow built-up anchorage members 26 which are fashioned from sheet metal parts and welded to the under side of the center strip 10. At their bottom ends, the locking pins 24 engage in pockets 27 provided in a built-up closure and retaining member 28 which closes the bottom of the receiving pocket for the spring unit, jointly formed by the channel members 5 of the sliding sill 1 and the fixed stops 21, where-to the stops 22 are secured. The bottom closure member 28 (see Fig. 3) is transversely reinforced against bending or distortion by the hollow stiffening construction 29 at its opposite ends, and secured to the bottom flanges of the channels 5 by means of screw bolts 30. In addition to supporting the locking pins 24, the closure member 28 thus serves to hold the parts of the buffer spring unit assembled in the car frame. At the top, the pocket for the buffer unit is closed by a cover plate 31 which along its side edges is welded to the top flanges of the side channels 5, said plate being bifurcated at its ends as at 33 (Fig. 2) to clear the locking pins 24, and stiffened intermediate its ends by an upwardly projecting box-like formation 34 (Fig. 3). This formation 34 functions in cooperation with the sides of the pockets 25 as presently explained to limit the extent of movement of the center sill 1.

As a consequence of this construction and arrangement, it will be seen that when the sliding center sill 1 moves rightward, relative to the underframe of the car, the stops 21 (at the left in Fig. 2) on the channels 5 will cause the pressure plate 20 to move away from the adjacent fixed stop 22 on the car frame with the result that the

spring unit 15 is further compressed. In a like manner when the sliding center sill moves to the left, the stops 21 (right hand in Fig. 2) on the channels 5 will cause the corresponding pressure plate 20 to move away from the adjacent fixed stop 22 on the car frame and thereby bring about further compression of the spring unit. In this way the shocks attending starting and stopping of the trains in which the car is interposed will be effectively absorbed and the strains on the frame proportionately minimized. The extent to which the spring unit 15 may yield is determined by encounter of the projection 34 on the sliding center sill 1 with the wall of one or the other of the fixed pockets 25, depending upon the direction in which the shock is transmitted.

To facilitate assembling and placement of the spring unit 15 into the car frame in accordance with our invention, we have provided a holder which is generally designated by the numeral 35 and illustrated in perspective in Fig. 12, and a wedge element (whereof two are needed) which is comprehensively designated by the numeral 40 and illustrated in perspective in Fig. 13.

As shown, the holder 35 is in the form of a clamp of U-shaped configuration with relatively short upwardly tapering jaws 36 whereof the inner faces 37 are perpendicular to the top surface 38 of a connecting bar 39. Preferably, the holder 35 is fashioned from sheet metal parts which are welded together along mutually abutting surfaces; although, if desired, it may be otherwise formed as by casting or forging. In practice, the spacing of the jaws 36 of the holder is somewhat less than the spacing of the stops 21 on the channels 2 of the sliding sill 1, and such as to accommodate the desired number of spring elements 16 and divider plate elements 17 together with the two end pressure plates 20, with said spring elements under definite initial compression which may vary in accordance with the size of the unit or the size of the car in which the unit is to be used. Any suitable means may be employed to compress the series of the elements composing the unit to a point where the holder may be slipped over them for temporary retainment by the latter as the pressure is slightly released on the pack.

As shown in Fig. 13, each of the wedges 40 has a shank 41 with a bevel 42 at its upper end, and a laterally projecting head 43 at its lower end.

With the spring unit under compression and engaged in the holder 35 as above explained, the assemblage is brought up to the underframe of the car from beneath in the manner shown in Figs. 8-11. From Fig. 9 it will be noted that the width of the clamp 35 is such as to allow its ends 36 to be passed up between opposite pairs of the stops 21 on the sliding sill 1. After the spring unit 15 is positioned in its pocket in the car frame, as shown in Fig. 8, the wedges 40 are forced upward between one pair of end stops 21 and the corresponding end pressure plate 20 as shown in Figs. 8 and 9, with the result that said unit is further compressed and the clamp 35 thereby released for removal. With this accomplished, the bottom closure member 28 is thereupon applied with the pins 24 in place within the pockets 27 as shown in Fig. 10, and this assemblage raised into position with incidental engagement of the upper ends of said pins into the sockets 25, whereupon the closure member 75 is made fast by means of the nut bolts 30 to hold

the spring unit 15 in place. All that remains to be done now is to remove the wedges 41 which can be accomplished by means of a suitable extracting tool, or said wedges may be freed by exertion of a sudden rightward pull upon the sliding center sill 1. Upon withdrawal of the wedges 41 as just explained, the pent up pressure in the elements 16 of the spring unit 15 will cause the right-hand end pressure plate 20 to fall back upon the right-hand stop 22 on the closure member 28, as in Figs. 2 and 3. From Figs. 10 and 11 it will be observed that the closure member 28 is provided with openings 44 to clear the wedges 40.

The draft gears 45, respectively, at opposite ends of the sliding sill may be of any approved type, and may have incorporated in them spring units like the one above described in association with the sliding center sill.

The alternative buffing means illustrated in Figs. 14-16 is characterized by having a double spring unit, that is to say, a spring unit composed of two aligned spring sections 15a. As shown, each of these sections 15a consists of a series of spring elements 16a in alternation with plate separators 17a, and end pressure plates 20a, 20b of which the latter is somewhat thinner than the former. As before, the pressure plates 20a at the end of the unit respectively abut the longitudinally spaced transversely aligned pairs of stops 21a on the channels 5a of the sliding center sill 1a. The inner or contiguous pressure plates 20b of the sections 15a, however, bear against a positionally fixed pin 24a centrally of the underframe of the car, said pin having its upper end engaged in a socket 25a at the underside of the floor strip 10a and its lower end engaged in a reinforced opening 27a in the bottom closure member 28a. While in the illustrated instance, the pin 24a is made to hollow rectangular cross sectional configuration from sheet metal parts welded together, it may, if desired, or found to be more convenient in practice, be cast, forged or otherwise constructed. Projecting inward from the channels 5a into the interval between the contiguous end pressure plates 20b of the two spring sections 15a are center stops 46, see Fig. 16, with which the spring sections 15a also cooperate as later explained. In the modification, the plate 31 is provided with limit stops 34a at opposite ends thereof. In other respects the alternative construction is identical with the first described embodiment of our invention, wherefore in Figs. 14-16, all corresponding parts, not specifically referred to above, are identified with the same reference numerals previously employed, except for the addition in each instance, of the letter *a* for convenience of distinction.

The implements provided in accordance with our invention for use in assembling the elements of the spring units of Figs. 14-16, and for applying the unit to the car frame, include a clamp 35a and a pair of wedges 40a, which latter are exactly like the wedges 40 of the first embodiment. The clamp 35a differs, however, from the clamp 35 of the first embodiment in that it is provided with an aperture 47 centrally of the top of its cross bar 38a to clear the lower end of the pin 24a, as shown in Fig. 14.

In assembling the double spring unit, the pin 24a is interposed between the two sections 15a and the unit then placed under a definite degree of initial compression in the same manner as the spring unit of the first embodiment, whereupon the clamp 35a is applied to receive the pack in

the interval between its jaws, with the lower end of the pin 24a cleared in the aperture in the cross bar of said clamp. The loaded clamp 35a is thereupon brought up to the car frame from beneath, and the double spring unit slipped into position in the interval between the paired stops 21a on the channels 5a of the sliding center sill 1a, the upper end of the pin 24a being at the same time engaged in the socket 25a on the cover strip 10a, all as shown in Fig. 14. The wedges 40a are next driven upwardly between the pressure plates 20a of one end pair and the corresponding stops 21a on the sliding center sill (Fig. 14), whereby the sections 15a are compressed slightly to release the clamp 35a which can thereupon be withdrawn downwardly. With the double spring unit thus positioned in the car frame, the bottom closure member 28a is brought up so that the lower end of the pin 24a is received in the aperture 27a, and made secure by means of the nut bolts 30a as shown in Fig. 15. The wedges 40a are thereupon removed and the right-hand end pressure plates 20a of the unit thereby allowed to move into contact with the contiguous stops 21a on the sliding center sill 1 under the inherent pressure of the spring sections 15a. The installation of the alternative spring unit can thus be effected as quickly and easily as the spring unit of the first embodiment. With the compound unit in place, it will be seen that as the sliding center sill 1a is moved to the right relative to the car frame incident to starting of the train, for example, the pressure plate 20a of the left-hand section 15a will be correspondingly moved by the contacting stops 21a on said sill, thereby placing said section under greater compression to absorb any attendant shocks, while the right-hand section 15a will remain passive since it is merely carried along with the sill by virtue of being engaged between its corresponding stops 21a and the center stops 46. On the other hand when the pull on the sliding center sill 1a comes from the left, the right-hand section 15a will operate in a similar manner while the left-hand section remains passive.

Contact of the upstanding stops 34a on the sliding sill 1a respectively with the fixed projections 26a, will determine the limit of movement allowed said sill relative to the car frame and also the limits of compression of the respective spring sections 15a.

Having thus described our invention, we claim:

1. Buffing means according to claim 10, in which the spring unit includes a pack of flat resilient spring elements in alternation with plate separators.

2. Buffing means according to claim 10, in which the spring unit includes a pair of end pressure plates, and a pack of flat resilient spring elements in alternation with plate separators interposed between said end pressure plates.

3. Buffing means for a railway car or the like, having a longitudinal guideway medially of its underframe, and a sliding draft element with laterally spaced side members movable endwise in the guideway, said means comprising a compression spring unit lodged in the interval between the side members of the draft element; opposing pairs of inwardly projecting stop abutments on the side members of said draft element normally engaged by the opposite ends of the spring unit; a bottom closure member removably secured to the underframe crosswise of the guideway to hold the spring unit in place; and fixed stop abutments for the spring unit spaced

to correspond with the movable stop abutments of the draft element and normally transversely aligned with the latter, said fixed stop abutments being engaged in the bottom closure member and extending upward into the interval between the side members of said draft element.

4. Buffing means for a railway car or the like having a longitudinal guideway extending medially of the length of its underframe, and a sliding draft element with laterally spaced side members movable endwise in the guideway, said means comprising a compression spring unit lodged in the interval between the side members of the draft element centrally of the underframe; opposing pairs of inwardly projecting stop abutments on the side members of the draft element normally engaged by the opposite ends of the spring unit; a bottom closure member removably secured to the underframe at the center crosswise of the guideway to hold the spring unit in place; and fixed stop abutments for the spring units spaced to correspond with the movable stop abutments on the sliding draft element and normally transversely aligned with the latter, said fixed stop abutments being engaged in the bottom closure member and extending upward into the interval between the side members of said draft element.

5. Buffing means for a railway car or the like having a longitudinal guideway medially of its underframe and a sliding draft element with laterally spaced side members movable endwise in the guideways, said means comprising a compression spring unit lodged in the interval between the side members of the draft element; opposing pairs of inward stop projections on the side members of the draft element normally engaged by the opposite ends of the spring unit; a bottom closure member removably secured to the underframe crosswise of the guideway to hold the spring unit in place; and fixed end abutments for the spring unit in the form of pins spaced to correspond with the removable stop abutments on the draft element and normally transversely aligned with the latter, said pins having their lower ends engaged in sockets on the closure member and their upper ends engaged in sockets provided for them on said underframe above said sliding draft element.

6. Buffing means for a railway car or the like having a longitudinal guideway medially of its underframe and a sliding draft element with laterally spaced side members movable endwise in the guideways, said means comprising a compression spring unit which is composed of two endwise aligned sections, and which is lodged in the interval between the side members of the draft element; opposing pairs of inwardly projecting stop abutments on the side members of the draft element engaged by the remote ends of the aligned spring sections; a bottom closure member removably secured to the underframe crosswise of the guideway to hold the spring unit in place; and a fixed stop abutment common to the inner ends of the two spring sections engaged in said bottom closure member and extending upward into the interval between the side members of said draft element.

7. Buffing means according to claim 10, including means for limiting the endwise movement of the draft element in the guideway and for limiting the extent to which the spring unit can be compressed in operation.

8. Buffing means for a railway car or the like having a longitudinal guideway extending medi-

ally of the length of its underframe, and a sliding draft element with laterally spaced side members movable endwise in the guideway, said means comprising a compression spring unit which is composed of two endwise aligned sections and which is lodged in the interval between the side members of the draft element centrally of the underframe; opposing pairs of inwardly projecting stop abutments on the side members of the draft element engaged by the remote ends of the aligned spring sections; a bottom closure member removably secured to the underframe at the center crosswise of the guideway to hold the spring unit in place; and a fixed stop abutment common to the inner ends of the two spring sections engaged in said bottom closure member and extending upward into the interval between the side members of said draft element.

9. Buffing means for a railway car or the like, having a longitudinal guideway medially of its underframe and a sliding draft element with laterally spaced side members movable endwise in the guideways; said means comprising a compression spring unit which is composed of two endwise aligned sections and which is lodged in the interval between the side members of the draft element; opposing pairs of inwardly projecting stop abutments on the side members of the draft element engaged by the remote ends of the aligned spring units; a bottom closure member removably secured to the underframe crosswise of the guideway to hold the spring unit in place; and a fixed stop abutment in the form of an upright pin common to the inner ends of the two spring sections, said pin having its lower end engaged in an aperture in the bottom closure member and having its upper end engaged in a socket provided for it on said underframe above said sliding draft element.

10. Buffing means for a railway car or the like having an underframe with a longitudinal guideway, and a draft element with laterally-spaced side members movable endwise in the guideway, said means comprising a compression spring unit lodged in the interval between the side members of the draft element; opposing pairs of transversely-arranged inwardly-projecting stop abutments on said side members spaced longitudinally of the latter and normally engaged by the opposite ends of the spring unit; a bottom closure member removably secured to the underframe crosswise of the guideway to support the spring unit and thereby hold it in place; and fixed stop abutments for respectively engaging the opposite ends of the spring unit, said fixed stop abutments being spaced longitudinally of the guideway by a distance corresponding with the lengthwise spacing of the stop abutments on the draft element and projecting upwardly from the closure member into the interval between the side members of said draft element.

11. Buffing means for a railway car or the like having an underframe with a longitudinal guideway, and a draft element with laterally-spaced side members movable endwise in the guideway, said means comprising a compression spring unit consisting of two similar serially arranged components, lodged in the interval between the side members of the draft element; pairs of transversely-aligned inwardly-projecting stop abutments on said side members spaced lengthwise of the latter and constituting movable abutments for the remote ends of the two components of the spring unit; a closure member removably secured to the underframe crosswise of the guide-

way; and a fixed stop element projecting from the closure member through the interval between the side members of the draft element into engagement with the contiguous inner ends of the two components of the spring unit.

12. Buffing means for a railway car or the like according to claim 11, in which the closure member is secured to the underframe at the bottom to support the spring unit from beneath and thereby hold it in place; and wherein the fixed stop element projects upward from the closure member through the interval between the side members of the draft element.

13. Buffing means for a railway car or the like having an underframe with a longitudinally-slotted center sill and a draft element with laterally-spaced side members which extends continuously through the slot of the center sill for guidance to endwise movement therein, said buffing means comprising a compression spring unit lodged in the interval between the side members of the draft element; a pair of transversely-aligned inward projections on said side members together constituting a movable abutment for one end of the spring unit; a removable plate secured to the bottom of the center sill crosswise of the slot in the latter; and a fixed stop element projecting upward from the plate in the interval between the side members of the draft

element for engagement by the other end of the spring unit.

14. Buffing means for a railway car or the like having an underframe with a longitudinally-slotted center sill and a draft element with laterally-spaced side members which extends continuously through the slot of the center sill for endwise guidance therein, said buffing means including a compression spring unit lodged in the interval between the side members of the draft element; a pair of transversely-aligned inward projections on said side members together constituting a movable abutment for one end of the spring unit; a removable plate secured to the bottom of the center sill crosswise of the slot in the latter beneath the spring unit to hold it in place; and a fixed stop element projecting upward from the plate in the interval between the side members of the draft element for engagement by the other end of the spring unit.

15. Buffing means according to claim 14, in which the fixed stop element is in the form of a removable pin having its lower end engaged in a socket in the closure plate and its upper end in a socket provided by a fixed cover plate extending crosswise of the slot of the center sill at the top.

FREDERICK W. HANKINS.
WENDEL J. MEYER.
